Patented January 26, 1904.

UNITED STATES PATENT OFFICE.

GEORG MORITZ CALBERLA, OF DRESDEN, GERMANY.

APPARATUS FOR COATING CIGARETTE-PAPER WITH LEAF METAL.

SPECIFICATION forming part of Letters Patent No. 750,255, dated January 26, 1904.

Application filed November 21, 1901. Serial No. 83,137. (No model.)

To all whom it may concern:

Be it known that I, GEORG MORITZ CALBERLA, a citizen of the Kingdom of Saxony, residing at Dresden, in the Kingdom of Saxony, German Empire, have invented certain new and useful Improvements in Apparatus for Coating Cigarette-Paper with Leaf Metal; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Up to the present time gilded mouthpieces of cigarettes were when not handwork made with the aid of devices in which the leaf metal coming from a bobbin was at regular intervals clamped by a blunt-edged tool erroneously called "cutter" to a table or board below and then severed or torn asunder by the pull exercised on it by the gummed cigarette-paper. This tearing asunder produces a very irregular line of separation and gives rise to much waste both of metal and cigarettes. In order to do away with these drawbacks, the present invention separates the device for checking or clamping the leaf metal when it is to be severed from the device which carries out this severing, attributing these operations to separate members. Furthermore, the device for severing is in this invention not merely a blunt tool clamping the leaf metal to be thereupon torn, but a member making a drawing cut, and may consist in either a straight or circular knife, a saw, a thin wire thread, or the like.

Figure 1 is a front elevation of the machine with the block which carries the clamping-plates shown in vertical section. Figs. 2 and 3 are detail views, partly in elevation and partly in section, showing two different positions of the block. Fig. 4 is a side elevation of the block and cutter-head with the cutter lowered.

Above the table *a*, over which the protecting-strip *b* together with the leaf metal *c*, Figs. 2, 3, move, two clamping-plates *d* *e* are movable up and down. When the feed of the metal strip is to be arrested, these come down on the latter and clamp it to the table *a*, Fig.

2. In the meanwhile a knife *f* between the clamping-plates descends and cuts off a piece of the leaf metal *c* with a drawing cut, the knife being adjusted to exactly descend exactly so far as to cut the metal only, and not the paper *b* as well. The leaf metal being held firmly against the table on both sides of the knife, cannot move under it, and the result is a clean cut in just the proper place. When the cut is completed and the severed piece of leaf metal is to be pasted on the gummed portion of the cigarette-paper passing over the revolving roller *g*, the clamping-plates *d* *e* are raised as well as the knife *f* to allow the leaf metal to pass on.

To prevent the metal strip from possibly sticking to the rear clamp *e* when the latter rises and disturbing the good operation of the apparatus, a scraper *h* may be provided, holding down the metal when the clamps rise.

As the scraper *h* and the knife *f* may receive their motions in any suitable manner from other moving parts of the cigarette-machine, it is not deemed necessary to give a detailed description thereof, the motion of the knife being only indicated.

The knife *f* consists of a thin steel blade mounted in a slide *i*, which may be moved to and fro by a rod *k* on the block *l*, carrying the clamping-plates *d* *e*. Inside the slide *i* two side plates *m* are adjustably attached by screws *n* to the sides of the knife-blade *f* and may be accurately adjusted in relation to the block *l*, the table *a*, and the paper strip *b* with the aid of wedges *p* and screws *o*.

The up-and-down motion of the clamping-plates is derived from cams *q* by means of vertically-guided rods *r*, fastened to the block *l*. In this block the clamping-plates are given a certain amount of vertical play and are actuated upon by springs *t*, sunk into the block *l* and pressing on pins *v* of the clamping-plates *d* *e*. Thus the latter in coming down on the metal strip exercise an elastic pressure on the same, but nevertheless clamp it down sufficiently firmly on the table *a*. When the block, with its slide *i*, descends, the plates *d* *e* first clamp the leaf metal, and then the knife, moving down with the block, comes down on the leaf metal and severs it in consequence of its lateral motion relatively to the block *l*. Si-

multaneously with the downward motion of the clamping-plates *c*, the roller *x*, which has to press the severed piece of leaf metal to the cigarette-paper strip, is moved out of contact 5 with the roller *g* in order to interrupt the feed of the paper strip *b* and the metal strip *c* while the latter is being held by the plates *d* *e* and cut by the knife *f*. This motion of the roller *x*, acting also as guide-roller for the paper 10 strip *b*, is derived from a cam *y*, revolving about the center *y'*, and the projecting portions of which press against an arm *z* of an oscillating lever *z'*, carrying the roller *x*, and thereby temporarily removing the latter from 15 the paper *w*, Fig. 1 in dotted lines. During this position of the roller the plates *d* *e* are clamping the leaf metal. After one of the 20 projections of the cam *y* has passed by the arm *z* of the lever *z'* the roller *x*, actuated by the spring *l*, flies up against roller *g* and 25 presses the piece of leaf metal previously severed on the gummed cigarette-paper.

The position and length of the projections of the cam *y* correspond to the position and 25 length of the leaf-metal piece which is to adhere to the cigarette-paper and to the position and length of the parts of the cigarette-paper to be coated and not to be coated with leaf metal, so that all the operations described take 30 place at their proper time.

The distance of the roller *x* from the cutting device may be so chosen that the piece 35 of leaf metal made to adhere to the cigarette-paper by the roller *x* is not the last, but a previously-cut piece.

The adhesive or gum is imparted to the cigarette-paper by a projecting revolving wheel 2, receiving paste or gum of any kind 40 from rollers 3 4 5, these and the wheel being made to revolve by cog-wheels 6 7 8 9. In a similar manner the smoothing and drying of the portions of the cigarette-paper *w* coated with metal is effected by a revolving are 10, which when it comes in contact with the cigarette-paper presses the latter against the roller *g* above it. Instead of this are, though, a smooth 45 roller might be employed, which is removed at certain intervals from the roller *g* in a similar way as described in the case of the roller *x*. This periodically-interrupted pressing of the 50 coated cigarette-paper has not only the purpose of pressing and smoothing the coatings, but also that of leaving the paper to itself during the interruptions to prevent permanent 55 stresses from arising in the same, which is very important for the good feed of the paper onto the printing apparatus.

What I claim, and desire to secure by Letters Patent, is:

60 1. In a machine of the class described, the combination with the continuously - rotating roller over which the cigarette-paper passes, of a feeding and pressing roller for the leaf metal operated by the continuously-rotating 65 roller, means to throw the pressing-roller into

and out of engagement with the cigarette-paper whereby the feed of the leaf metal is interrupted and the pressing of the same intermittently effected, means to clamp and sever the leaf metal during the interruption 70 of the feed, and a knife reciprocating between said clamping means, substantially as described and shown and for the purpose set forth.

2. In combination with a continuously-operating roller over which the cigarette-paper passes, a feeding and pressing roller for the leaf metal rotated by the continuously-rotating roller, means to intermittently interrupt the feed of the leaf metal, means for clamping and severing the leaf metal during the interruption of the feed, and means to operate the clamping means, consisting of vertically-guided rods, fastened to the clamping means and operated by continuously-rotating cams, 85 substantially as described and shown and for the purpose set forth.

3. In a machine for coating cigarette-paper with leaf metal, the combination of the bed-plate and the means for feeding the leaf metal 90 over the same, means to interrupt the feed of the leaf metal, clamping-plates adapted to engage the leaf metal with a yielding pressure, during the interruption of the feed, a cutter operating between the plates, and means to 95 effect a draw cut, substantially as described and shown and for the purpose set forth.

4. In a machine of the class described, the combination with the bed - plate over which the leaf metal passes, a feeding and pressing 100 roller for the leaf metal, means for interrupting the feeding of the same, means for clamping and cutting the leaf during the interruption of the feed, said means consisting of a reciprocating block, clamping-plates carried by 105 the block and having a yielding connection therewith, a cutter mounted between the plates, and means to effect a draw cut, substantially as described and shown and for the purpose set forth.

5. In a machine of the class described, the combination with a bed-plate over which the leaf metal passes, a feeding and pressing roller for the leaf metal, means for interrupting the feeding of the same, means for clamping and cutting the leaf during interruption of the feed, said means consisting of a reciprocating block, having a recess formed therein, a spring in said recess, clamping-plates carried by the block and engaged by said spring whereby 115 the plates engage the leaf metal with a yielding pressure, and a cutter operating between 120 said plates, substantially as described and shown and for the purpose set forth.

In testimony whereof I affix my signature in presence of two witnesses,

GEORG MORITZ CALBERLA.
